UNITED STATES PATENT OFFICE.

ROBERT GRUBB, OF POWERS LAKE, NORTH DAKOTA.

PLOW.

1,155,917.

Specification of Letters Patent.

Patented Oct. 5, 1915.

Application filed January 13, 1915. Serial No. 2,014.

To all whom it may concern:

Be it known that I, ROBERT GRUBB, a citizen of the United States, residing at Powers Lake, in the county of Burke and State of North Dakota, have invented a new and useful Plow, of which the following is a specification.

This invention relates to plows and more particularly to means for detachably securing the share to the moldboard, one of the objects of the invention being to provide attaching means which is simple, durable and compact, can be readily manipulated, and which is in a position where it will not interfere with the ordinary operation of the plow.

With the foregoing and other objects in view which will appear as the description proceeds, the invention resides in the combination and arrangement of parts and in the details of construction hereinafter described and claimed, it being understood that changes in the precise embodiment of the invention herein disclose, can be made within the scope of what is claimed, without departing from the spirit of the invention.

In the accompanying drawings the preferred form of the invention has been shown. In said drawings:—Figure 1 is a perspective view of the plow inverted to show the present improvements. Fig. 2 is a perspective view of the share and point landside inverted. Fig. 3 is a perspective view of a portion of the frog, adjacent parts being broken away. Fig. 4 is an enlarged section on line A—B Fig. 1. Fig. 5 is a perspective view of the coupling lever forming a part of the present improvements.

Referring to the figures by characters of reference 1 designates a frog the inwardly extending wing 2 of which is provided, at its forward or front edge with a notch or recess 3. The outer side of the frog, which is substantially triangular, is provided, near the point, with a longitudinally extending key 4 which is dovetailed in cross sectional contour and has a transverse shoulder 5 from which the key is gradually reduced in thickness toward its front end, as shown in Fig. 4. A moldboard 7 is adapted to be fastened in the usual or any preferred manner to the wing 2 of the frog and pivotally connected to the moldboard as at 8 is a bell crank lever 9 provided with spaced notches 10 and 11 in one arm thereof. The notch 10 is de-

signed to engage a headed stud 12 extending from the moldboard 7 so as thus to be held tightly against the under surface of the moldboard.

The plow share 13 is adapted to lap the front end of the frog and to abut against the forward edge of the moldboard, this share being provided at one side with a point landside 14, provided with a dovetailed groove 15 for the reception of the key 4 when the said point landside is shifted longitudinally onto the key. This longitudinal movement of the point landside into position is limited by the shoulder 5 on the key. A headed stud 16 extends downwardly from that end of the share remote from the point landside and is adapted to be received within the notch 11 so that the said share will thus be tied to the moldboard. Another headed stud 17 extends from the share at a point adjacent the point landside and is adapted to be received within the notch or recess 3 and to be engaged by a hook 18 or the like provided at the forward end of a rod 19. The rear portion of this rod adjustably engages one arm of lever 9 and is held thereto in any suitable manner, as by means of a nut 20. A landside plate 21 may be bolted or otherwise secured upon the outer side of the frog 1 so as to abut against the back end of the point landside.

It will be apparent that when the studs 16 and 17 are engaged by the lever 9 and the rod 19 respectively, the share will be held securely to the moldboard and cannot be accidentally displaced. However, by disconnecting rod 19 from lever 9, said lever can be swung about its pivot 8 so as to release the stud 16 and rod 19 can be disengaged from the stud 17 so that the share can thus be slipped forwardly to disengage its point landside from the key 4.

What is claimed is:—

1. In a plow, the combination with a frog having a recess extending into the front portion of the inwardly extending wing thereof, and a longitudinally extending key upon the point of the outer side of the frog, of a moldboard, a share, a point landside carried thereby and insertible into engagement with the key, a projection upon the share and movable into the recess in the frog, a lever fulcrumed upon the moldboard, means upon the share and adapted to be detachably engaged by the lever, and means adjustably engaging one arm of the lever

for simultaneously drawing the projection on the share rearwardly into the recess in the frog and shifting the other arm of the lever laterally to press against the lever engaging means on the share, whereby a simultaneous backward and lateral pull is exerted upon the share relative to the moldboard and frog.

2. In a plow, the combination with a frog
10 having a recess extending into the front edge portion of the inwardly extending wing thereof, of a moldboard, a share, a point landside carried by the share and adapted to engage the outer side of the
15 frog, a projection upon the share, a lever fulcrumed upon the moldboard, means upon the share for engagement by one arm of the

lever, and means engaging the projection and the other arm of the lever and adjustable relative to the lever for simultaneously 20 drawing the projection rearwardly into the recess in the frog and swinging the other arm of the lever against the lever engaging means on the share to thrust said means laterally, thereby to bind the point landside 25 against the frog.

In testimony that I claim the foregoing as my own, I have hereto affixed my signature in the presence of two witnesses.

ROBERT GRUBB.
